UNITED STATES PATENT OFFICE.

OTIS E. ALWINE, OF ELKHART, INDIANA

GATE.

1,117,622.

Specification of Letters Patent. Patented Nov. 17, 1914.

Application filed June 1, 1914. Serial No. 841,978.

To all whom it may concern:

Be it known that I, OTIS E. ALWINE, a citizen of the United States, residing at Elkhart, county of Elkhart, and State of Indiana, have invented new and useful Improvements in Gates, of which the following is a specification.

My invention relates to improvements in gates, more particularly to tilting gates; 10 and the objects of my improvements are, first, to provide effective and simple means for tightening the wires of the gate frame; second, to provide a gate frame that is simple and of low cost of construction; third, 15 to provide effective tilting and latching means not exposed to view or the weather.

Other objects will appear and be more apparent herein, and the new and novel features thereof fully described.

20 On the accompanying drawings—Figure 1 is a side elevation of the closed gate—in full lines—and an open gate in dotted lines; Fig. 2 is a rear elevation showing the lifting levers, chains and lever posts; Fig. 3 is 25 a longitudinal section through the lifting lever casing showing the actuating mechanism assembled therein. Fig. 4 is a section through Fig. 3 on the line IV—IV. Fig. 5 is a fragmentary plan view, in section, of 30 the lifting lever casing and parts; Fig. 6 is a cross section on line VI—VI of Fig. 2. Fig. 7 is a view of a tightener pin for tightening the gate frame wires, and a wire end; Fig. 8 is a section on the line V—V of Fig. 35 3; Fig. 9 is a fragmentary section of the gate frame, latch, latch rod and gate post; Fig. 10 is a section in elevation of the same parts.

The gate frame, on the drawings annexed 40 hereto, is composed of a single piece of bent pipe, or tubing, having top, bottom and end members 1, 1^a, 1^b and 1^c integrally formed from a single piece of pipe. The members 1^a and 1^c are formed at their ends for arrangement within the ends of the lifting lever casing 3 which, together with suitable vertical and horizontal wires 30 form and complete the gate proper.

45 Gate post 2 is disposed in a convenient position adjacent member 1^b of the gate frame and carries latch slot 23 formed therein. Upright forked posts 4 are set in the ground at a convenient point and carry hand levers 5 pivoted on the lever pins 6. 50 Lifting lever casing 3 comprises a main body member 3^b and a cover plate 7 which,

when bolted or fastened to 3^b, forms an elbow for connecting, or joining, gate frame members 1^a and 1^c which are arranged within and fastened in the open ends thereof at 60 44 and 45, respectively. Lever casing 3 carries a lifting lever 8 having the latch crank 13 and chain levers 9 formed thereon, and disposed in half boxes 10 and 11 of members 3^b and 7. Levers 9 have holes 12 formed 65 therein for receiving an end link, or pin, of the lifting chain 38. The branch lifting chain 39 runs from chain 38 to and connects with eyescrew 25 which is screw threaded into casing 3 at 43 passing through the hole 70 26 of the gate member 1^c to retain same within the end of casing 3. The casing cover plate 7 is bolted, or fastened, to member 3^b by means of the flanges 31 and 34, and flange bolts 33 penetrate bolt holes 32 75 and 34^a formed in said flanges of said members, thereby securely clamping gate frame member 1^a within the casing 3 at the forward end 44.

Horizontal wire members 30 are fastened 80 to the gate member 1^b in any suitable manner and secured at the opposite ends to gate members 1^b by tightener pins 27 which carry the eye 29 therein, and the tightener nut 28 thereon. The pin 27 penetrates the holes 42 85 formed in the gate member 1^c and has the wire 30 bent through the eye 29 and twisted upon itself for security.

Casing 3 carries the entire gate frame in its finished condition and is journaled in the 90 boxes 36 within which the ends of the shaft 35, carried by casing 3, operate. Openings formed at 37 are formed for carrying the shaft 35 which may be fastened therein in any suitable manner. Boxes 36 are set into 95 posts 4 and fastened thereto by screws 41.

The lifting lever shaft is loosely arranged 100 within its bearings 10 and 11 formed in the casing 3 to insure an absence of friction. The latch crank 13 is engaged loosely by the latch- 105 rod hook 14 which hooks over same. The opposite end of the hook 14 is screw threaded at 17^a into an enlargement 17 of the latch-rod 18 and carries a coil spring 15 seated against the washer 16 carried by hook 14, on one 110 end, and seated on the lugs 7^a and 3^a formed, respectively, on cover plate 7 and main body member 3^b, at the other end thereof. The latch-rod 18 is arranged within the gate frame member 1^a and extends therein for 115 its entire length, projecting through the end thereof at the hole 24 formed in member 1^a,

carrying at its outer screw threaded end 19, the latch 20, the latch handle 21 and the nut 22. The latch rod 18 penetrates hole 21^a of the handle 21 and may be formed of any material suitable for the conditions to be met. By a suitable arrangement of the parts a wire cable may be substituted therefor and the same results obtained. The nut 22 is screw threaded on rod 18 to set latch handle 21 tightly against the back of the latch 20.

When the gate is closed the latch-rod 18 is projected forward by the action of the coil spring 15, thereby throwing latch 20 into the latch socket 23 of the gate post 2, which locks the gate. When it is desired to open the gate a sharp pull on the lever 5 accomplishes it in the following manner: The lifting chain 38 lifts lever 9, which is normally parallel with gate member 1^a, to a vertical position, thereby raising the crank 13 and retracting the latch-rod and latch 20 from the socket 23 in the gate post 2. A further application of power on lever 5 lifts and tilts the gate frame until it swings into the position shown in dotted lines in Fig. 1 of the drawings hereto annexed. To close the gate, a pull on the lever 5 is transmitted through chain 38 and the branch 39 to the eyescrew 25 fastened in the upper end 30 of the casing 3. As the gate descends and is closing the latch 20 contacts with the face of the post 2 and is retracted thereby, but springs forward into the socket 23 when the gate frame is at rest in a closed position.

Having fully described my invention, I claim:

1. The combination with a gate post and a latch retainer thereon; of a pivotally mounted gate adapted to swing vertically, said gate having a hollow longitudinal frame member, a combination lifting lever and crank mounted upon the lower frame member of the gate, means applicable to said lifting lever for swinging the gate upon its pivot shaft, a latch operating member yieldably arranged within the longitudinal frame member, connected with and operable by said lifting lever and crank, and a latch mounted upon one end of the latch operating member adapted to engage the latch retainer.

2. In a tilting gate, the combination with a pivot shaft and bearings therefor; of a gate mounted upon said shaft and comprising a lifting lever casing secured to said shaft, pivotal therewith, and adapted to form a part of the gate frame, a gate frame member of tubular formation having top, bottom and end members with spaced ends, said lever casing being adapted to receive said spaced ends of said tubular gate frame member to form and complete the gate frame construction, a lifting lever shaft arranged within the lever casing and extending to the exterior thereof, and means applicable to

said lifting lever shaft for swinging the gate upon its pivot shaft.

3. In a gate, the combination with a pivot shaft and supports therefor; of a gate mounted upon said pivot shaft and comprising a lifting lever casing upon which said pivot shaft is mounted, top, bottom and end members of a gate frame formed of a single length of tubular material having spaced ends secured to said lever casing, a lifting lever mounted upon the lever casing, a latch operating member arranged within the bottom member of the gate frame and connected with the lifting lever, means applicable to said lifting lever for swinging the gate upon its pivot shaft, and latch arranged at one end of the latch operating member and connected therewith, said latch and operating member adapted for retraction by said gate swinging means.

4. In a tilting gate, the combination with a gate post and a latch retainer thereon; of a pivoted gate adapted to swing vertically and comprising a lifting lever casing adapted to form a section of the gate frame, a tubular gate frame member having spaced ends, said spaced ends of said frame member being secured to the lifting lever casing to complete the gate frame, a lifting lever mounted upon the lever casing and in rotative relation therewith, a latch operating member yieldably arranged within the lower tubular frame member, connected with the lifting lever and operable thereby, a latch mounted upon one end of the latch operating member adapted to engage the latch retainer, and means applicable to said lifting lever for swinging the gate upon its pivot shaft, said latch adapted for retraction by the gate swinging means.

5. The combination with a pivot shaft and supports therefor; of a gate pivotally mounted upon the shaft and comprising a casing borne by the pivot shaft, a tubular gate frame having its spaced ends secured to said casing, a lifting lever mounted upon the gate and adapted to engage gate swinging means, a yieldable latch operating member arranged within the tubular bottom member of the gate frame retractile by the lifting lever, a latch attached to one end of the latch operating member, retractile therewith, and adapted to engage a latch retainer.

6. The combination with a pivot shaft and supports therefor; of a gate pivotally mounted upon the shaft and comprising a casing borne by the pivot shaft, a tubular gate frame having its spaced ends secured to said casing, a lifting lever mounted upon the gate and adapted to engage gate swinging members, a yieldable latch operating member arranged within the tubular bottom member of the gate frame retractile by the lifting lever, a latch attached to one end of the latch operating member, retractile there-

with, and adapted to engage a latch retainer, a lifting member engaging the lifting lever, and a gate actuating lever connected with the lifting member.

5 7. A gate provided with a lifting lever casing pivotally mounted, a cover plate mounted upon said casing, journal boxes formed in said lever casing, a rotative lifting lever arranged within said boxes and 10 adapted to receive gate lifting members.

8. In a tilting gate, the combination of a lifting lever casing provided with a pivot shaft, said casing being adapted to form a section of a gate frame, a gate frame mem-

ber having spaced ends secured to the extremities of the lever casing to complete the gate frame, a rotative lifting lever mounted upon the lever casing and adapted to receive gate lifting members, a crank carried by the lifting lever, and tension means for holding 20 the crank in a predetermined position.

In testimony whereof I have hereunto fixed my signature in the presence of two witnesses.

OTIS E. ALWINE.
